CLAIM

The ornamental design for a tricep push down machine, as shown and described.

DESCRIPTION

FIG. 1 is a front perspective view of a tricep push down machine, showing my new design;

FIG. 2 is a rear perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The dashed broken lines in the figures are for the purposes of illustrating portions of the tricep push down machine, which form no part of the claimed design.

1 Claim, 8 Drawing Sheets
